INVENTOR
John A. Hasenpflug.

UNITED STATES PATENT OFFICE.

JOHN A. HASENPFLUG, OF CLEVELAND, OHIO, ASSIGNOR TO THE CHAMPION SAFETY LOCK AND NOVELTY COMPANY, OF SAME PLACE.

SASH-LOCK.

SPECIFICATION forming part of Letters Patent No. 527,686, dated October 16, 1894.

Application filed March 9, 1894. Serial No. 502,984. (No model.)

To all whom it may concern:

Be it known that I, JOHN A. HASENPFLUG, a citizen of the United States, residing at Cleveland, in the county of Cuyahoga and State of Ohio, have invented certain new and useful Improvements in Sash-Locks; and I do hereby declare that the following is a full, clear, and exact description of the invention, which will enable others skilled in the art to which it applies to make and use the same.

My invention relates to improvements in sash locks, and the invention consists in the construction of a lock substantially as shown and described and particularly pointed out in the claims.

In the accompanying drawings, Figure 1 is a bottom view of the lock complete, and showing the parts in the relation they sustain when the lock is open. Fig. 2 is a like view of the same parts, and showing the lock as it appears when half way closed. Fig. 3 is a cross-section of the lock and meeting rails of the two sashes on a line corresponding to 3, 3, Fig. 2, the same showing the relation of all said parts when they are in the half way position. Fig. 4 is a bottom perspective view of the lock case and a part of the mechanism connected therewith. Fig. 5 is a top perspective view of the locking bolt or reach. Fig. 6 is a perspective view of the cam alone. Fig. 7 is a plan view of the bolt or reach, and showing the cam in the relation therein as it appears before the reach or bolt is drawn inward to bring the sashes together. Fig. 8 shows the cam in its opposite position and as it appears when the sashes are drawn together.

A represents the case or shell of the lock, provided with a central hub —2— projecting inward and adapted to receive the post or spindle B which has the handle —3— rigid therewith. This post or spindle B has a square or angular part —4— just beneath the hub —2—, upon which is fitted the cam C to rotate with said post. This cam is made a separate member, and adapted to fit upon the part —4— of the post so as to be practically rigid therewith. As here shown, it has an arm or projection —6— at one side, but the form of the cam may be largely varied and serve the same purpose, its object and use being to draw the bolt or reach D back into the casing

A so as to bring the sashes tightly together. Said bolt or reach D has its edge —7— adapted to engage the part E on the opposite sash after the usual way, and it is supported upon the lower extremity of the post B beneath part —4— by the head, washer or nut on the bottom of said post. The shank or neck —8— operating in said bolt is circular in cross-section, and the said bolt has a longitudinal slot —9— in which said shank works and which makes the bolt free to slide back and forth on said post within the limits of said slot. About the top of said slot said post is provided with a depression or cavity —10— of sufficient width and depth to accommodate the cam C, which is set wholly into said cavity and is flush with the top surface of the bolt. There also is a lateral recess —11— at one end of the cavity —10— adapted to receive and pocket the cam point —6— of the cam C when the bolt is in the position shown in Figs. 1 and 2, or in any intermediate position between said points; but when the bolt is thrown into full locking position by carrying the handle —3— around to the position shown in dotted lines at the right of Fig. 2, the cam —6— will be turned from its pocket —11— with its arm against the end of the recess —10— which will force the said bolt back and thus cause it to draw the sashes together. Meanwhile the bolt is confined to a certain back and forth movement and cannot turn by reason of a lug —14— on its top and rear which engages in the groove or channel —16— at the side of hub —2— on the inside of the casing A, as clearly seen in Fig. 4. This channel in the main is concentric with the post or spindle B, and the said lug —14— is confined therein in all its operations. When the parts are in the relation shown in Fig. 1, and the bolt is within the case, the lug —14— is in the circular part of said channel, and when it is drawn back the lug enters the space —17— and then the bolt is kept from turning and can only slide back and forth.

When the parts are in the position, as in Fig. 1, the cam C is in relation as in Fig. 7, and the lug —14— ready to turn into channel —16—, or to slide into —17—, according as the handle is turned one way or another. If the handle is in position, as in Fig. 2, and

is then turned to position in dotted lines said figure, the cam projection —6— will be withdrawn out of the recess —11— and forced around into the position shown in Fig. 8 and 5 the lug —14— will enter channel —17— and effectually lock the bolt against being turned by an instrument from the outside, or otherwise than by the handle. In the reverse movement the cam C acts first by turning handle 10 —3— back to half way place and bringing lug —14— to curved channel —16—. Then a further turn restores all the parts to place as in Fig. 1 and the lock is open and retired.

When the cam C enters its projection —6— 15 into recess —11— as the handle reaches the position in Fig. 2 from the position in dotted lines said figure, the bolt becomes engaged with or by the cam and is forced to rotate from position in Fig. 2 to position in Fig. 1.

20 Having thus described my invention, what I claim is—

1. In a sash lock, the casing formed in a single piece, the handled post, a cam fixed rig-

idly on said post inside the casing, and the locking bolt suspended on said post beneath 25 said cam and constructed to be engaged and operated by the cam, said bolt having a projection on its top, and a channel and stop on the inside of the top of the casing for said projection, substantially as set forth. 30

2. The casing having a hub on its inside about the post hole and a channel at one side of said hub, the handle post extending through said hole, a cam on said post beneath its hub, and a locking bolt provided with a longitudinal slot through which the said post passes and constructed about said slot for engagement by the said cam and having a projection to engage in the said channel about the said hub, substantially as set forth. 35 40

Witness my hand to the foregoing specification.

JOHN A. HASENPFLEG.
